UNITED STATES PATENT OFFICE.

JOHN B. O'CONNOR, OF AURORA, ILLINOIS, ASSIGNOR TO LYON METALLIC MANUFACTURING COMPANY, OF AURORA, ILLINOIS, A CORPORATION OF ILLINOIS.

METHOD OF MANUFACTURING SHELVING.

Application filed June 19, 1920. Serial No. 390,129.

To all whom it may concern:

Be it known that I, JOHN B. O'CONNOR, a citizen of the United States, residing at Aurora, in the county of Kane and State of Illinois, have invented a certain new and useful Improvement in Methods of Manufacturing Shelving, of which the following is a specification.

My invention relates to shelving, and more particularly to methods of manufacturing the shelves themselves. The invention applies primarily to the production of sheet metal shelves having side and end flanges by which they may be stiffened and fastened to the uprights. Sheet metal shelves having end flanges are well known, but heretofore, the forming operation was always gauged from the opposite edge of the sheet. This gave rise to several disadvantages. In the first place, the gauge was located at a considerable distance from the point of action of the forming die, especially in operating on the larger sizes of sheets. Second, if the sheets were not accurately sheared or blanked, the flange would be inaccurately positioned and the shelf would be out of true. One of the objects of my invention is to provide a method for eliminating these difficulties. Another object is to provide a method by which various stock sizes of shelves may be produced from the same form of die. Still another object is to provide a system of punching and flanging by which one row of holes may be utilized for fastening the shelves to the upright partitions and another row for gauging the sheet during the flange forming operation.

I accomplish my objects in accordance with a method which will be more readily understood by referring to the accompanying drawings in which—

Figure 1 shows in full lines, a blank of the largest size obtainable from a given size of sheet. The dotted lines show a blank of smaller size produced from the same size original sheet, thus illustrating how the same size sheet and same blanking, punching and forming dies may be employed for producing a smaller size shelf.

Figure 2 is a perspective view of a portion of a finished shelf;

Figure 3 is a detail showing one corner of the blank;

Figure 4 is a fragmentary sectional view 55 showing the configuration of a portion of

the shelf after the same is completely formed.

Like numerals denote like parts throughout the several views.

It will be understood by those familiar with manufacturing conditions and shop practice, especially in the iron and steel trades, that sheets are usually shipped from the mill in standard sizes. This promotes economy in various ways and it is usually more expensive to order sheets of special size from the mill than it is to order standard sizes and cut away the surplus material. According to my method, I take a sheet 1 having dimensions sufficient to make a shelf 2 of the largest size which it is proposed to produce. I then punch holes 2 in it in rows parallel to the sides and ends of the sheet, the holes being placed at equal distances apart and the rows being at right angles to each other.

The subsequent operations are performed by utilizing the holes, in connection with gauge pins, for gauging the sheet. One operation is to notch out the corners, as at 4, 80 Figures 1, 2 and 3. If a shelf of maximum size is wanted, nothing but this corner is removed, but if a sheet of smaller size is wanted, as indicated in dotted lines in Figure 1, then the sheet is sheared also. In 85 any event, the operations are performed with the gauge pins in the holes, and hence the final configuration is bound to be accurate. Usually two pins are found to be sufficient. After the sheet is completely blanked it is 90 subjected to the action of the forming die or dies. One of these forms the lip 6 and another forms the flange 7, so that the appearance will be as shown in Figures 2 and 4.

During the forming operation, I place the 95 gauge pins not in the holes nearest the edge, but by preference in the holes next to them, that is, in the second row of holes. One advantage in this is that the gauges are thus close to the part of the sheet which is being configurated instead of at a distance therefrom, as in the previous methods where the sheet is gauged from the opposite edge. This produces a sheet in which the shearing, notching and forming will be 100 perfectly accurate with respect to a nearby row of holes and by repeating the operation for all four edges of the sheet, the resulting shelf will be true at all four sides. In other words, the flanges will be positioned 105 110

relatively to the holes and independently of the edges of the sheet. The shape of the sheet may be inaccurate, but the flanges will nevertheless come at right angles to each other.

By not placing the gauge pins in the outer row of holes, I am able to and do so flange the sheet that the outer row of holes comes in the flange 7 and may thus be used for 10 bolt holes for fastening the shelves to the upright partitions of the shelving (not shown).

To give a concrete example as to how this method may be worked out in practice, let 15 it be assumed that the manufacturer proposes to furnish shelves in lengths varying, by three inches. He punches the sheet on three inch centers, the outer row coming $\frac{1}{2}$ of an inch from the adjacent edge. Then, 20 using the next to outer row for the gauge pins, the sheet is corner-notched and flanged, the outer break 10 coming $\frac{1}{2}$ of an inch from the edge of the sheet and the inner break 12 coming $1\frac{1}{2}$ inch from the edge. This produces a flange 7 which is one inch wide with 25 the outer row of holes half way between the upper and lower edges of the flange. If a smaller shelf is desired, three inches, or a multiple of three inches, is cut from an end 30 or side or both. This reduction in the size of the sheet produces a corresponding reduction in the size of the shelf but necessitates no change whatever in any of the dies or formers. Thus, by operating ac- 35 cording to my method any standard size

shelf may be obtained from a single set of dies, the dies required being only those required for configurating one edge of the sheet. Furthermore, these dies although used separately for all sides of the sheet pro- 40 duce a shelf which is true and accurate in every respect.

Having thus described my invention, what I claim as new and desire to secure by Letters Patent is:

1. The method of producing flanged rectangular sheet metal shelves consisting in perforating a sheet to form rows of holes parallel to a given sheet edge with corresponding holes of the several rows forming rows of holes at right angles to the direction of the first rows, using a given row of holes as sockets for receiving gauge pins, and then flanging the edge adjacent to and contiguous with the row of holes used as gauge pin sockets.

2. The method of producing flanged sheet metal shelves consisting in punching the sheet with a plurality of rows of holes parallel to a given edge, using holes other than those nearest to a said edge for the reception of gauge pins, and flanging the sheet with a flange wide enough to bring the outer row of holes within the flange, whereby the outer row may be used as bolt holes for fastening the shelves in place.

In witness whereof, I have hereunto subscribed my name.

JOHN B. O'CONNOR.
